No. 674,494.

Patented May 21, 1901.

M. J. BROTT.

SHOE-LACE HOLDER.

(Application filed Oct. 9, 1899. Renewed Oct. 26, 1900.)

(No Model.)

UNITED STATES PATENT OFFICE.

MARY J. BROTT, OF DES MOINES, IOWA.

SHOE-LACE HOLDER.

SPECIFICATION forming part of Letters Patent No. 674,494, dated May 21, 1901.

Application filed October 9, 1899. Renewed October 26, 1900. Serial No. 34,472. (No model.)

To all whom it may concern:

Be it known that I, MARY J. BROTT, a citizen of the United States, residing at Des Moines, in the county of Polk and State of Iowa, have 5 invented a new and useful Shoe-Lace Holder, of which the following is a specification.

My object is to provide an improved device specially adapted to facilitate detachably fastening the ends of lacing-strings together and 10 to a shoe to prevent the annoyance incident to lacing-strings of shoes and corsets from becoming untied, and by providing a neat, strong, durable, and efficient clasp adapted to be permanently attached to one of the mating parts 15 of a shoe, corset, and other garments that are to be laced together for detachably fastening the ends of strings securely together.

My invention consists in the device herein-after set forth, pointed out in my claims, and 20 illustrated in the accompanying drawings, in which—

Figure 1 is a perspective view of a shoe as required for practical use and shows the shoe laced and the ends of the laces extended 25 through the clasp and tucked inside of the shoe. Fig. 2 is a longitudinal sectional view of the clasp in a closed and locked position. Figs. 3, 4, and 5 are diagrammatical views of the forms of the three pieces of metal plate 30 that are combined in the construction of the complete device. Fig. 6 is a transverse section of the device, showing the end portions of lacing-strings clamped fast therein. Fig. 7 is a perspective view showing my invention 35 in an open position and fixed to a top portion of a shoe.

The letter *a* designates a metal plate that has a narrowed extension *b* at one end adapted to serve as a member of a hinge-joint in connecting it with another plate of corresponding size in such a manner that the two plates can overlie each other to clamp the end portions of a lacing-string together. It has an opening *c* at its other end to admit a hook. 40 A mating plate *d* has a transverse slot *f* at one end to admit the part *b* of the plate *a* and a square opening *g* at its other end for the passage of a hook or curved lever *h*, hinged thereto. The plate *a* has longitudinal corrugations or beads *m*, adapted to enter corresponding grooves *m'* in the plate *d* when the plates are in overlying position, as shown in Figs. 1, 2, and 6, and as required to bite and clasp lacing-strings placed between the overlying plates. The plate *d* has a perforation 50 *r* at one end through which a rivet is extended for pivotally connecting the device to a shoe, as shown in Fig. 7. It also has an elongated slot *s*, through which the ends of lacing-strings may be passed to aid in securely fastening them by means of the clasp.

In the practical use of my invention when applied as shown and when laced as required before tying the ends of the strings together in a common way I extend them over the under plate *d* and then press the upper hinged plate *a* upon the strings and fasten it down in overlying position relative to the plate by passing the free end of the curved lever *h* through the coinciding openings *g* and *c* and 55 press it into a clamping position, as shown in Fig. 2, to lock the ends of the plates together.

It is obvious if desired the ends of the strings thus clamped fast may be also tied together and their free end portions tucked in 60 the top of the shoe. 65

Having thus described the construction, application, and operation of my invention its utility will be obvious, and

What I claim as new, and desire to secure 70 by Letters Patent therefor, is—

1. A fastener for the ends of lacing-strings consisting of two elongated metal plates hinged together and provided with coinciding openings at their free ends for the passage of a lever, corrugations in the plates to bite upon lacing-strings, a lever hinged to the free end of the under plate and adapted to pass through said coinciding openings in the free ends of the two overlying plates, and 75 means for fastening the one end of the under plate to a shoe, arranged and combined to operate in the manner set forth for the purposes stated.

2. A device for fastening lacing-strings, 80 comprising a curved metal plate having one end adapted to be riveted to one of the mating top parts of a shoe and its other end portion

provided with an opening for the passage of the free end of a lever, a curved lever hinged to said plate, a mating curved plate hinged to one end of the said first-mentioned plate to overlie it and provided with an opening that will coincide with the opening in the first-mentioned plate to admit the passage of the free end of the said curved lever, arranged and combined to operate in the manner set forth for the purposes stated.
